UNITED STATES PATENT OFFICE

2,039,774

DOOR STRUCTURE

Charles G. Bryson, Erie, Pa., assignor to Erie
Restaurant Equipment Company, Erie, Pa., a
corporation of Pennsylvania

Application June 9, 1931, Serial No. 543,118

2 Claims. (Cl. 16—131)

In many door structures, such as the doors of ovens, cookers, cold storage and refrigerator doors, etc. it is desired to maintain a sealed connection between the door and the door seat. 5 Ordinarily this is accomplished by providing one of the seating faces with a yielding material and as the door is used the seating material wears, or recedes from its original position and when this happens a complete seal is finally lost. 10 The present invention is designed to provide an adjustable means for the door whereby adjustment may be made for yielding or variation in the seating material. Features and details of the invention will appear from the specification and claims. 15

A preferred embodiment of the invention is illustrated in the accompanying drawing as follows:—

Fig. 1 shows a front view of the structure. 20 Fig. 2 a section on the line 2—2 in Fig. 1. Fig. 3 a section on the line 3—3 in Fig. 1. Fig. 4 a perspective view of one of the hinge connections.

Fig. 5 a perspective view of the adjustable hinge 25 block.

1 marks the door frame. This has a door opening 2 surrounded by a raised seat 3. A door 4 is provided with a groove 4a in which is placed a gasket, or seating material 4b.

30 The door is provided with hinge knuckles 5. A hinge mounting bar 6 is secured to the frame by screws 7. Loops 8 extend outwardly from the bar 6, said bar forming a support for the loops. The loops form slots 9 receiving hinge blocks 35 10, the sides of the slots forming guide surfaces for the blocks. The hinge blocks slide in and out in the loops, or in other words, toward and from the frame. The blocks have grooves 10a and the blocks are locked in the loops by screws 11 which extend into the grooves 10a holding the blocks in the slots 9, and when they are 40 adjusted lock them in adjustment by engaging the inner wall of the groove. A screw 12 extends through the outer end of the loop and is adapted to adjust the block toward and from the frame. A hinge pintle 13 extends through the knuckles and the blocks. It is provided with a head 14 which prevents it from dropping through the knuckles and blocks.

The door is provided with a cam latch surface 15 and a latch 16 has a projection 17 which extends through a screw-threaded sleeve 18. A nut 19 secures the projection in the sleeve and the nut is locked in place by a cotter pin 20. The 5 sleeve 18 operates in a screw-threaded opening 21 and is locked in adjustment by a nut 22. It will readily be seen that by adjusting the sleeve the latch may be adjusted toward and from the frame and the sleeve may be locked in whatever 10 adjustment it may be extended to by the lock nut. It will also be observed that by adjusting both the hinge and the sleeve the door may be kept in proper relation to the seat on the frame and a perfect seal maintained between the gasket 15 and the seat. I preferably make the opening 21 of sufficient diameter to permit the entrance of the nut 19 so that the handle with the sleeve assembled may be run into place. If, therefore, there should be any loosening of the nut the 20 sleeve may be readily removed and the nut adjusted. A stop pin 24 is provided which is engaged by the handle as the handle is thrown to open position.

A set screw 23 is provided locking the pin 25 with the knuckle of the door. In consequence all wear is between the pin and the block and should wear take place all that is necessary is to renew the pin and the block to secure complete alinement. 30

What I claim as new is:—

1. A hinge structure comprising a hinge loop having opposing guide surfaces; a hinge block 35 slidably mounted in the loop in engagement with said guide surfaces; a hinge knuckle; a pintle connection between the block and knuckle; an adjusting screw for adjusting the block in the loop; and a screw operating against the side of the block locking the block in adjustment.

2. A hinge structure comprising a hinge loop 40 having guide surfaces therein; a hinge block slidably mounted in the loop in engagement with the surfaces, said block having a guide groove therein; a hinge knuckle; a pintle means connecting the block and the knuckle; and a screw 45 extending into the groove holding the block slidably in the loop and adapted to lock the block in adjustment.

CHARLES G. BRYSON.
